UNITED STATES PATENT OFFICE.

EDWARD E. ZIEGLER, OF PHILADELPHIA, PENNSYLVANIA.

DESIGN FOR A BRAKE-RING.

SPECIFICATION forming part of Design No. 34,111, dated February 19, 1901.

Application filed January 23, 1901. Serial No. 44,475. Term of patent 7 years.

To all whom it may concern:

Be it known that I, EDWARD E. ZIEGLER, a citizen of the United States of America, and a resident of Philadelphia, in the county of 5 Philadelphia, State of Pennsylvania, have invented a new and original Design for a Brake-Ring for Coaster-Brakes, of which the following is a specification.

My invention relates to a ring employed in 10 that class of brakes used for bicycles or other vehicles commonly known as "back-pedaling" or "coaster" brakes.

Referring to the drawings accompanying 15 this application, Figure 1 illustrates a front elevation of a brake, showing my new design; and Fig. 2 illustrates a vertical section taken on line 2 2 of Fig. 1.

As shown in the drawings, the leading or material feature of my design consists in the

shape or configuration of the hub 1 and the 20 cup-shaped disk 2, the hub having arranged on one end a series of internal flat surfaces 3 and at the opposite end an internal thread 4. The disk 2 has a flat face 5, which is curved inwardly, forming a slightly-tapered portion 25 6, terminating in a rim 7.

Having described my invention, what I claim, and desire to secure by Letters Patent, is—

The design for a brake-ring substantially 30 as herein shown and described.

Signed at Philadelphia, Pennsylvania, this 21st day of January, 1901.

EDWARD E. ZIEGLER.
